[57] CLAIM

The ornamental design for an egg carton, as shown and described.

DESCRIPTION

FIG. 1 is an exploded perspective view of an egg carton in open position, showing my new design;

FIG. 2 is a left side elevation thereof, in closed position, the right side elevation being a mirror image;

FIG. 3 is a top plan view of FIG. 2 thereof;

FIG. 4 is a front elevation of FIG. 1, in closed position, the rear side elevation being a mirror image; and

FIG. 5 is a bottom plan view of FIG. 4 thereof.

FIG. 1

FIG. 2

FIG. 3

FIG. 4

FIG. 5
